Primary Examiner — Jae Liang*Assistant Examiner* — Ji Sun Yoon(74) *Attorney, Agent, or Firm* — Dunlap Bennett & Ludwig, PLLC(57) **CLAIM**

The ornamental design for a wrap with wax seal stamp, as shown and described.

DESCRIPTION

FIG. 1 is a front left perspective view of the wrap with wax seal stamp, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof, shown in use. Broken lines shown in the drawings depict text on the wax seal stamp that forms no part of the claimed design. Other broken lines shown in FIG. 8 represent environment of a bottle that forms no part of the claimed design.
